UNITED STATES PATENT OFFICE.

EDGAR THOMAS WORSWICK, OF NILGIRI, MADRAS, BRITISH INDIA.

APPARATUS FOR THROWING CONFETTI AND THE LIKE.

1,324,092.

Specification of Letters Patent.

Patented Dec. 9, 1919.

Application filed November 14, 1918. Serial No. 262,484.

To all whom it may concern:

Be it known that I, EDGAR THOMAS WORSWICK, a subject of the King of Great Britain and Ireland, residing at Station Hospital, 5 Wellington, Nilgiri, Madras Presidency, British India, have invented a new or Improved Apparatus for Throwing Confetti and the like, of which the following is a specification.

0 This invention relates to a new or improved apparatus for throwing confetti, rice and the like at weddings. It may also be used for throwing articles of light weight such as inexpensive presents or toys, and in 5 India, colored powders such as are thrown during certain native festivals, may be substituted.

In its simplest form the invention consists of a tube of cardboard or other suitable material containing a small explosive charge at one end, ignitable by any suitable means, the remaining portion of the tube being filled with confetti or other material or articles. The end of the tube above the confetti is 10 closed by a thin paper cover pasted over it, and the other end by a disk of cardboard attached to the tube by paste and, if desired, reinforced with a strip of cloth pasted to both the disk and tube, or that end of the 15 tube may be made in one piece with the tube.

An embodiment of the invention is illustrated in the accompanying sheet of drawings, in which: *a* designates the tube, *b* the thin paper end closure, and *c* the stouter closure at the opposite end reinforced by a strip of cloth *d*. Within the tube is provided a cone *e* of sand- or glass-paper, the sanded or glass-covered surface forming the 20 inside of the cone. Within the said cone is placed an explosive charge *f* ignitable by the withdrawal of a string *g* which passes through a perforation in the end closure *c* into the cone *e*, its inner end having a bulb *h* 25 of sand or powdered glass attached to it by gum or other adhesive. The cone is held in position by a light packing of crumpled tissue paper or other suitable material *i*, and is

separated by a similar wad *j* from the confetti. The remaining space *k* in the tube is 50 filled with confetti or other desired material.

The propellant used is composed of the following ingredients in the proportions stated, namely:—

Fulminate of silver	8.5 grains.
Fulminate of mercury	17.0 grains.
Potassium chlorate	74.5 grains.

Or, to increase the loudness of the explosion, 60 the following may be used:

Fulminate of silver	10.0 grains.
Fulminate of mercury	15.5 grains.
Potassium chlorate	74.5 grains.

Owing to the sensitiveness of the propellant, the charge is necessarily filled into the cone in a moist or pasty condition which causes it to adhere to the surface of the cone on drying.

In using the apparatus the string *g* is smartly pulled so that the friction caused by the bulb *h* passing through the explosive charge *f* ignites it and discharges the confetti or other contents of the tube through 75 the end closure *b*.

Having now particularly described and ascertained the nature of my said invention and in what manner the same is to be performed, I declare that what I claim is:—

A confetti projector comprising a casing, a hollow friction member in the casing, near one end of the latter, a cushioning packing in said end of the casing and around said friction member, a charge of confetti in the 85 casing, a solid explosive charge arranged for movement in the friction member for ignition thereby, and a cord attached to said explosive charge and projecting from the first named end of the casing.

In witness whereof I have signed this specification in the presence of two witnesses.

EDGAR THOMAS WORSWICK
